(57) **CLAIM**

The ornamental design for a juvenile toothbrush handle, as shown and described.

DESCRIPTION

FIG. 1 is a front elevation view of the juvenile toothbrush handle of our new design;

FIG. 2 is a right side elevation view thereof, the left side being a mirror image;

FIG. 3 is a rear elevation view thereof;

FIG. 4 is a top plan view thereof; and,

FIG. 5 is a bottom plan view thereof.

The bristles and action figure are shown in the above figures in broken lines for illustrative purposes only and form no part of the claimed design. The particular action figure shown within the juvenile handle is a Registered Trademark of Lego Systems A/S, a Danish Corporation and as stated above, this action figure is representative and is not part of the claimed design.
